UNITED STATES PATENT OFFICE.

HENRY PRICE BALL, OF PITTSFIELD, MASSACHUSETTS.

FOOD-CHOPPER.

1,219,423.

Specification of Letters Patent. Patented Mar. 20, 1917.

Application filed May 5, 1914. Serial No. 836,403.

To all whom it may concern:

Be it known that I, HENRY PRICE BALL, a citizen of the United States, residing in the city of Pittsfield, county of Berkshire, and 5 State of Massachusetts, have invented a certain new and useful Food-Chopper, of which the following is a specification.

This invention relates to devices for chopping foods (meat, vegetables, etc.), and is 10 ordinarily intended for household purposes. The objects I have in view are: first, to reduce the number of loose parts to the minimum; second, to provide for the interchange of cutters of different sizes without de- 15 tached parts; third, to make the chopper self-cleaning so that all of the food will be discharged from the forcer into the cutter; and fourth, to render the device suitable for use upon materials containing a great deal 20 of liquid. These and further objects will more fully appear from the following specification and accompanying drawings, con- 25 sidered together or separately.

In the drawings, Figure 1 is a front elevation of a food chopper embodying my invention;

Fig. 2 is a side view of the same, the hopper and a portion of the body being in section;

Fig. 3 is a sectional view on the line 3—3 of Figs. 1 and 2;

Fig. 4 is a sectional view of the body with the forcer removed;

Fig. 5 is a rear elevation of the device;

Fig. 6 is a front view of the discharge end of the forcer; and

Fig. 7 is a side view of the same.

In all of the views, like parts are designated by the same reference characters.

40 The device primarily comprises three parts, the body 1, the forcer 9, and the cutter 16. The body and forcer while each is made of several elements, are so connected together that they cannot be separated in use 45 and therefore no parts can be lost.

The body 1 comprises a barrel portion 2 with a cylindrical opening extending entirely through it. Above the barrel is a hopper 3 for admitting food. The barrel is 50 supported in proper position by means of a bracket 4. This bracket has attached to it the clamp 5 so that it may be applied to a table or other suitable support. Within the cylindrical opening of the barrel are forcing threads 6. These are spirally arranged, as

shown. They extend from the inlet end *a* to the outlet end *b* of the barrel. Within the first and second threads of the inlet end are limber holes 7. In advance of the first threads is a spout 8. More limber holes may be made if necessary.

The forcer 9 is actuated by means of a crank 12^a. The forcer is provided with a long thread 11 and a short thread 12. The long thread extends substantially through the entire length of the forcer. The short thread 12 extends from about the discharge end of the hopper to the discharge end of the forcer. These threads are shown of uniform pitch throughout (this, however, is not essential) and they are the same diameter as the opening in the barrel 2. Between these threads 11 and 12 are two intermediate threads 13 somewhat shorter than the thread 12. These intermediate threads 13 are of gradually increasing height (greater diameter) from the point of their inception to the discharge end of the forcer. The outer edge of each intermediate thread 13 from the beginning to within a short distance of the discharge end of the forcer is sharp. The front edge of the short thread 12 is also sharp. All of these threads adjacent the discharge end of the forcer, have a straight portion 14 parallel to the axis of the forcer. These 75 produce straight portions 15 in the grooves between the threads. The discharge portions of the grooves are substantially parallel to the axis of the forcer. Each groove at the straight portion has a short edge and a long edge as shown, and I prefer to make the long edge at least as long as the width of the groove, so as to form a firm support for the food which is forced against the cutter, and also to make the path of the food 80 perpendicular to the plane of cutters. 85

The cutter 16 is formed preferably of one piece of metal and of a plurality of integral cutting members, each having a group of cutting openings 17. The cutting openings in each member are of different sizes, as shown. In the embodiment chosen for illustration, the cutters have three, six and twelve openings respectively. I prefer to make the cutters of sheet steel of uniform thickness throughout. The cutter member with twelve cutting edges is shown in the operative position. The material forced through each groove in the forcer will be 90 chopped twelve times for each revolution of 95 100 105 110

the forceer. These cutters are grouped about an imaginary center at substantially 120° apart. Within each group of cutting openings is a central opening 18. This central opening engages with the end of the forceer and locks the cutter in place. The cutters are formed with side notches 19. On the body are brackets 20. In each bracket is a headed bolt 21. Two of the brackets are arranged one on each side of the cutter; the third bracket is below the same. The cutter may be introduced in place by sliding it vertically back of the headed parts of the bolts. The forceer is introduced in place in the body with its cutting end within the central opening 18 of that cutter which has been previously selected and which is in line with the central opening of the body. I prefer to make the supports for the cutter, as shown, of bolts so that they may be adjusted to accurately fit the thickness of the cutter. All the cutters are shown as located upon the same plane; but this is not necessary. Each cutter member is preferably cone shaped, as shown in Fig. 3, and the end of the forceer is similarly shaped, as shown in Fig. 7, so that an increased cutting surface is produced and a shearing cut is obtained. The cone shaped end makes the forceer and the cutter to at all times hug each other tight, irrespective of the wobble fit the forceer may have in the body, especially when worn from use.

For the purpose of holding the forceer in place and detachably and adjustably engaging it with the cutter, the following devices are employed:

A bearing ring 22 surrounds one end of the forceer and engages with a flange 23 thereon. A lock or presser lever 24 has a forked upper end which engages with the bearing ring on each side of the center of the forceer at diametrically opposite joints. This presser lever carries a screw 25 which presses against the bracket 4 and this screw has a scalloped edged head 26 so that it may be rotated and the pressure between the forceer and the cutter adjusted. The presser lever is held in place by means of a headed fulcrum pin 27 carried by the bracket 4. This pin passes through a slot 28 in the presser lever. By turning the head 26 the pressure upon the bearing ring 22 may be adjusted and consequently the pressure between the discharge end of the forceer and the cutter may be adjusted as desired. By rotating the head 26 the screw 25 may be disengaged from contact with the bracket 4. The presser lever can then be moved downward until the forked upper ends cease to engage with the bearing ring 22. The forceer may then be removed from the body. If it is desired to change the cutting members, the forceer must first be at least partly withdrawn so as to disengage its end from

the central opening 18 of the cutter; thereupon the three unitary cutting members are removed and given a partial rotation and replaced with the desired member in place. For the purpose of holding the bearing ring 22 in place, pins 29 are employed. To prevent the ring 22 from rotating, it is provided with a pin 30 which engages with one of the forks of the presser lever 24.

The operation is as follows:

The parts are assembled as shown in Figs. 1, 2 and 3. The food is introduced into the hopper 3. The screw 25 is adjusted to engage the end of the forceer with the cutter with the desired pressure. Upon rotation 70 of the crank the food is first forced toward the cutter by the action of the long thread 11 and forcing threads 6. Any undesirable excess of liquid in the food will be pressed out and pass through the spout 8. The triangular space in advance of the first thread 11, best shown in Fig. 4, is utilized to collect the juices preliminary to its ejection through the spout. Any juice which may be trapped in advance of the first thread 85 will enter this triangular space by means of the limber holes 7. The food will be forced forward by means of the long thread 11 and short thread 12 until it comes into contact with the sharpened ends of the short 90 threads 13, whereupon it will become bifurcated and each stream will enter the groove on each side of the short thread, and the four streams of food will be forced through the openings in the cutter. Before they 100 reach the cutter the direction of flow of the streams of food will be changed from a circular spiral path to a straight path parallel to the axis of rotation of the forceer. The point of alteration in the path of flow 105 from the spiral to the straight direction, will be far enough in advance of the cutter so that the long straight side of each groove will serve as a backing for the stream of food in each groove and hold it in the best 110 position to be acted upon by the cutter.

The parts may be separated for cleaning or for adjustment of the separate cutter members as previously described. One advantage of having the cutting take place between the forceer and the cutters is that when dulled or worn, new sharp ones may be substituted without getting a new body. It is to be understood that the parts illustrated are for the purpose of showing the principles of the invention only. The number of threads in the forceer and their pitch may be varied from that shown. Certain features of the invention will be attained by means of a cutter having more or less cutting members than that shown and the proportions and shapes of the pieces may be varied without departing from the spirit of the invention.

I have found this chopper can be used to 130

squeeze the juices of oranges and other fruit. While it will not remove the juice of meats which should have the juice remain in the meat, on the other hand it draws off enough of the water from cabbage and tomatoes to permit them to be chopped and prevent clogging. This feature of the invention also prevents liquid running out the back of the chopper and down on the floor as is often experienced with certain types on the market.

Having described my invention, what I claim as new and desire to secure by Letters Patent, is:

15. 1. A cutter for a food chopper, having a plurality of conical cutting surfaces radially disposed around a common center.
20. 2. A cutter for a food chopper, having a number of perforated conical cutting surfaces radially disposed around a common center.
25. 3. A cutter for a food chopper, having a number of circular groups of perforations radially disposed around a common center.
30. 4. A cutter for a food chopper, having a number of circular groups of perforations radially disposed around a common center, each group having a different size perforation.
35. 5. A cutter for a food chopper, made in one piece and of uniform thickness, having a plurality of separate groups of cutting elements.
40. 6. A cutter for a food chopper, formed of one piece of sheet metal, having several groups of cutting perforations radially disposed around a common center.
45. 7. A cutter for a food chopper, made in one piece and having several conical cutting elements, and means for selecting one element at a time to chop with.
50. 8. A cutter for a food chopper, having several conical cutting elements, radially disposed around a common center, and means for selecting one element at a time to chop with.
55. 9. A cutter for a food chopper, having several integral, conical members all connected by a common plane, each member having a group of cutter openings, said openings being diagonal to the plane.
60. 10. A cutter for a food chopper, having several integral members, each of which has a group of cutter openings of different sizes.
65. 11. A cutter for a food chopper, having several integral members radially disposed around a common center, each member having a group of cutter openings of different sizes.
70. 12. A cutter for a food chopper, having a plurality of sets of cutter openings of different sizes, associated together as a unit, and grouped around a common center.
75. 13. A cutter for a food chopper, having a plurality of sets of diagonal cutter open-
- ings, the sets arranged around a common center.
14. A food chopper, having a body, and a support for a cutter, in combination with a plurality of cutters of different sizes, associated together, and grouped around a common center.
15. A food chopper, having a body with a cylindrical opening, and supports for a cutter, in combination with a plurality of cutters of different sizes grouped around a common center, and combined in one structure.
16. A food chopper, having a body with a central opening, and supports for a cutter, in combination with a unitary cutter comprising different arrangements of cutting edges, located around a common center.
17. A food chopper, having a body, a forcer within the body, and a removable cutter having a central opening forming a bearing for the forcer, guides carried by the body, said guides and forcer acting to secure the cutter in position.
18. A food chopper, having a body with a central opening, a cutter support on each side of the opening, and a third support below the opening, in combination with a cutter having three elements, of substantially the same outside diameter, united to form a unitary structure with axes at substantially 120° apart.
19. A food chopper, having a body, a cutter carried by the body and having a plurality of sets of cutter openings, the sets grouped around a common center, and means for preventing the cutter from being rotated.
20. In a food chopper, a body, a cutter at one end, a forcer inserted in the body at the other end, and separate reciprocating adjusting means fulcrumed at the other end.
21. A food chopper having a body with spiral forcing threads, and a spout communicating with the body in advance of the first thread, there being a limber hole in one or more of the threads to permit juices to flow to the spout.
22. A food chopper, having a body and a forcer, a bearing on the forcer, a lever pivoted to the body engaging with the bearing, and means for applying pressure upon the lever.
23. A food chopper, having a body and a forcer, a bearing on the forcer, a lever having a slot, and a forked end, a headed pin on the body passing through the slot, and a screw on the lever coacting with the body to engage the forked end of the lever with the bearing.
24. A food chopper, having a body with a central opening, therein, supports on the body, a headed pin on the body, a lever having a slot engaging with the pin and also having a forked end, and a screw, in com-

4
bination with a cutter maintained within the supports on the bearing, and having a central opening in line with the center of the body opening, a force, one extremity of which engages with the opening in the cutter, a flange adjacent to the other extremity of the body, and a bearing surrounding the force and engaging with the flange, said

bearing being engaged by the forked end of the lever. 10

This specification signed and witnessed this 30th day of April, 1914.

HENRY PRICE BALL.
